UNITED STATES PATENT OFFICE.

PIERRE PLANTINGA, OF CLEVELAND, OHIO.

CLOSURE FOR RETORTS.

No. 911,524.

Specification of Letters Patent.

Patented Feb. 2, 1909.

Application filed May 22, 1908. Serial No. 434,305.

To all whom it may concern:

Be it known that I, PIERRE PLANTINGA, a citizen of the United States, resident of Cleveland, county of Cuyahoga, and State of Ohio, have invented a new and useful Improvement in Closures for Retorts and the Like and Operating Mechanism Therefor, of which the following is a specification, the principle of the invention being herein explained and the best mode in which I have contemplated applying that principle, so as to distinguish it from other inventions.

My invention relates to closures for the discharge openings of gas-retorts or the like, its object being to provide means whereby the door of the closure may be manipulated with safety to the operator, and at the same time effect a gas-tight contact between such door and that part of the retort surrounding the opening.

A further object of the invention is to permit of the use of an upright retort having a bottom opening, and in which the charge necessarily is borne by the door closing such opening, and at the same time increase the life of such door without impairing its effectiveness in the performance of its function.

The said invention consists of means hereinafter fully described and particularly pointed out in the claims.

In said annexed drawings:—Figure 1 is a side elevation of the lower end of a gas retort, closure and operating mechanism therefor embodying my invention, showing a part 35 of the retort in vertical axial section, such closure being shown as occupying its closed position. Fig. 2 is a vertical axial section of the said lower end of the retort together with a similar section of the closure, showing the 40 latter in a partially open position, the completely open position being shown in dotted lines. Fig. 3 is a bottom plan of the mouth-piece frame, closure and operating mechanism. Fig. 4 is a front elevation of same. 45 Figs. 5, 6, 7, 8 and 9 are views of detailed parts of the invention.

Referring to the drawings, A represents an ordinary upright retort used in the manufacture of gas. The lower end or mouth of the retort, from which the coke is removed after the gas-making process is completed, is provided with a closure and mechanism for operating same, which embody my invention.

Surrounding the lower end of the retort which is supported in any suitable manner

and suitably secured in place so as to be stationary, is a collar B, which is formed upon its lower end with a flange b. To the lower surface of this flange is secured a 60 mouth-piece frame C provided with a central opening c, which forms the lower end or mouth of the interior of the retort, and the flange c⁵, by means of which latter it may be secured to the collar B. The lower surface c' of this frame is planed off to form a contact or bearing surface for the door which engages the surface surrounding the mouth to form an air and gas-tight closure. Upon the rear of the frame and formed integrally therewith are two lugs c² c², Figs. 1 and 3, in which are formed horizontal bearings for an oscillatory rod D. This rod is formed with two eccentric journals d d, Figs. 5 and 6, which lie outside of and adjacent to the lugs 75 c² c² when the rod is in place in its bearings.

These journals d d occupy a position such as illustrated in Fig. 7, in which the eccentrics are above the axis of the rod, when the door is in its closing position, as will be 80 hereinafter more fully described. Upon these journals d d are mounted two oscillatory transverse bars E E, commonly referred to in the art as crossbars. The free or swinging end of these bars E E project 85 beyond the mouth of the retort and into the plane of movement of two latches F F. These latches are mounted upon pins c³ c³, Figs. 2 and 3, from which they depend and upon which they may freely oscillate, said 90 pins being suitably mounted upon lugs c⁴ c⁴ cast integrally with the mouth-piece frame, as will be readily understood. The horizontal distance between these lugs is made slightly greater than the thickness of the 95 latches, so that the latter may have a slight amount of lateral play in a direction perpendicular to their plane of oscillation. Each latch is provided with a nose f, Fig. 4, which form catches for the free ends of the 100 crossbars, by means of which the latter may be held in a substantially horizontal position as shown in Fig. 1. The lower ends of these latches are pivoted to a common connecting bar F', upon one end of which is pivoted a 105 connecting rod F². The outer end of the lateral rod is pivoted upon an operating lever F³ which is itself pivotally mounted upon a suitable hanger f' which is fixed to a suitable stationary support, such as the 110 floor plate A'. The upper end of each latch is provided with a stop f², which engages the

lower surface of the adjacent portion of the mouth-piece frame C, when the latches occupy their vertical positions, as shown in Fig. 4. Each latch is furthermore provided 5 with a curved or inclined surface f^3 , which may be engaged by the free ends of the cross-bars when the latter are swung upwardly, to throw the said latches out of their vertical position and permit the said crossbars to 10 move into their horizontal positions in which they may be engaged and held by the catches f. The stops f^3 prevent the latches from swinging into a position which will bring the bar F' into the path of the cross- 15 bars and thereby prevent the latter from moving upwardly as required.

As will be observed from the above described construction in which the operating lever F³ occupies a position lateral of the 20 mouth of the retort, that the latches may, from a position lateral of the retort, be moved to disengage or engage the cross-bars as may be desired.

The door G which closes the mouth of 25 the retort, is mounted upon the crossbars E E, in a manner hereinafter described and consists of two parts, an outer or main 30 concavo-convex member g and an inner or protecting concavo-convex member g', Fig. 2. The outer or main member g is formed with a circumferential flange provided with a bearing surface g² which is adapted to engage the bearing surface c' of the mouth-piece frame for forming the gas-tight junction 35 between the door and the retort. The inner member g' is also formed with a circumferential flange g³ which is, however, of less linear length than that of member g so that the member g' may be placed within 40 and be entirely surrounded by the flange of said member g, Fig. 2. Said member g' is secured to the main member with its concave surface opposing that of said main member as shown and its inner face g⁴ is 45 inclined relatively to the bearing surface g² of such main member, the inclination being upward from the pivoted side of the bar to the opposite side thereof, when the latter is in its closed position, as indicated in dotted 50 lines in Fig. 1. The said member g' is further formed with a central boss g⁵, Fig. 9, in which is formed a tee-slot g⁶, whereby a head of the bolt g⁷ may be introduced laterally into said boss. A central opening g⁸ 55 is formed in the main or outer member g for the reception of this bolt, the outer end of which is threaded to receive a suitable nut g⁹. By means of this construction it will be seen that the inner or protecting 60 member may be removably secured to the outer or main member.

Upon the bottom surface of the door G are formed two pairs of lugs g¹⁰ g¹⁰, through each of which a bolt C passes transversely, 65 Fig. 3. These bolts pass through the cross-

bars thereby forming a pivotal connection between such crossbars and the door, as will be readily understood.

Connecting the two crossbars E E is a transverse bar H, Figs. 1, 3 and 8. This bar 70 has its ends turned down to form journals h h, which are mounted in suitable cylindrical holes in the crossbars E E, forming bearings for such journals. The outer ends of the journals h are threaded to receive 75 suitable nuts, Fig. 3, which hold the bar in proper position, as will be readily understood.

Rigidly secured to or forming an integral part of the mouth-piece frame C is a downwardly projecting portion c", whose lower end is provided with a horizontal bearing for an oscillatory rod J. Keyed to this rod and located on each side of the bearing c' 80 are arms J' J'. Articulating with the ends of these rods are two members J² J², Fig. 3, whose outer ends are threaded and passed through the bar H. These ends are secured by means of suitable nuts j, j. The rod j 85 extends laterally of the retort and is provided with an operating lever J³, the oscillatory rod D being similarly provided with an operating lever D², these two levers and rods being so placed as not to interfere with each other's operations, as shown in Figs. 90 1 and 4. It will be noted that both the rods D and J may be actuated from a position lateral with respect to the retort.

Let it be assumed that the door is shut and secured in place, the charge in the retort is resting upon same, and the latter is held in place by the latches F F, the door and cross bars forming what I shall herein-after refer to as a stopper-member. In this position the operating lever J³ occupies 105 a position substantially horizontal, as shown in Fig. 1, operating lever D² occupying a position substantially vertical, as also shown in said figure in Fig. 1. If it is now desired to permit the discharge of the contents of 110 the retort, the operator throws the lever D² downwardly into the position shown in Fig. 2, and then grasps the lever J³ and the lever F³ is then moved to disengage the latches F from the crossbars E E. The point of application of the connecting members J² being placed intermediately of the ends of the stopper member and their pivotal axis or fulcrum, and nearer the free or swinging end thereof, a comparatively heavy weight may 115 be sustained by the application of the strength of the operator to the end of the lever J³. This lever is now lowered gradually by the operator to open the door G. As soon as sufficient space between the retort and door is obtained, the contents 120 thereof begin to discharge. The protecting plate g' placed as above described receives the contact of the discharging material, and being arranged in the inclined position pre- 125 130

viously described, diverts said material from the bearing surface g^2 of the main member g and thereby prevents any injury thereto or impairment of the integrity of its surface.

5 The action of the discharging material is illustrated in Fig. 2. It will be observed that these operations are all capable of being controlled from a position laterally of the retort, so that all danger to the operator due 10 to the discharge of the material or the movement of the closure is eliminated.

When it is desired to close the mouth of the retort, the operations above described are reversed, that is, operating lever J^3 is 15 first lifted so as to bring the crossbars E into their horizontal positions. This having been accomplished, the latches are moved to engage the crossbars as shown in Fig. 4. The lever D^2 is now moved upwardly to assume 20 the position shown in full lines in Fig. 1. This latter action brings the eccentrics from a position below the axis of the rod D to the position originally described above, a slight movement of the door in a transverse direction being thereby effected, first toward the rear and finally toward the front, the rear end of the cross bars being at the same time lifted up a short distance. The effect of 25 this movement is to produce a scraping or frictional action between the bearing surfaces c' and g^2 , whereby any obstruction in the form of dirt, dust or particles of coke are ground or pulverized so as to afford practically no impediment to the formation of 30 the required air and gas-tight joint. As previously mentioned, the distance between the two lugs c^4 c^4 is made such as to permit the latches F to be subjected to a slight lateral or transverse movement. This provision 35 is made so that these latches may move transversely with the door during the last described operation.

What I therefore claim and desire to secure by Letters Patent is:—

45 1. In a device of the character described, the combination with a stopper-member, of means for actuating said member and comprising mechanism for moving same toward and from the opening to be closed and mechanism operable independently of said first-named mechanism, for moving said member in a direction transverse with respect to such first-named movement.

50 2. In a device of the character described, the combination of a stationary mouth-piece frame provided with an opening, a stopper-member pivotally mounted and adapted to be swung into position to close said opening; an oscillatory rod connected with said stopper-member and an operating lever secured to said rod; such rod and lever being adapted to 55 actuate said stopper-member to assume its open and closed positions.

60 3. In a device of the character described, the combination of an upright retort having

a bottom opening; a stopper-member pivotally mounted and adapted to be swung into position to close said openings; a laterally-extending oscillatory rod connected with said stopper-member and an operating lever secured to said rod; such rod and lever being adapted to actuate said stopper-member to assume its open and closed positions.

4. In a device of the character described, the combination of an upright retort having a bottom opening; a stopper member pivotally mounted and adapted to be swung into position to close said opening; a laterally-extending oscillatory rod, connections between the latter and said stopper member, 75 said connections arranged so as to apply the force exerted thereby on the said stopper member at a point intermediate of the pivotal axis of the latter and its opposite end; and an operating lever secured to said rod; 80 said rod and operating lever being adapted to actuate said stopper-member to assume its open and closed positions.

5. In a device of the character described, the combination of an upright retort having a bottom opening; pivoted means adapted to be swung toward and from said opening; a door carried by said pivoted means, and means engaging said pivoted means intermediate of the extremities for actuating 95 same upon its pivotal axis.

6. In a device of the character described, the combination of an upright retort having a bottom opening; pivoted means adapted to be swung toward and from said opening; a 100 door carried by said pivoted means; an oscillatory rod and operating lever connected therewith; an arm secured to said rod, and a connecting member articulating with the end of said arm and connected with said pivoted 105 means.

7. In a device of the character described, the combination of an upright retort having a bottom opening; pivoted means adapted to be swung toward and from said opening; a 110 door carried by said pivoted means; an oscillatory rod and operating lever connected therewith; an arm secured to said rod; and a connecting member articulating with the end of said arm and secured to said pivoted means 115 intermediate of its extremities.

8. In a device of the character described, the combination of an upright retort having a bottom opening; means adapted to be moved toward and from said opening and comprising two bars each pivoted at one end and a transverse bar having its ends oscillatory mounted in said pivoted bars respectively; a door carried by said pivoted bars; an oscillatory rod and operating lever connected therewith; an arm secured to said rod; and a connecting member having one end articulating with the end of said arm and the other end secured to said transverse bar.

9. In a closure for retorts or the like, a 130

pivoted door comprising an outer or main member, and an inner member secured thereto and having a face in a plane inclined relatively to the plane of the bearing surface of said main member, the said bearing surface plane and inclined plane diverging from each other in the direction away from its pivotal axis toward the free or swinging end of said door.

10 10. In a closure for retorts or the like, a

door arranged to be placed in a horizontal position and formed with an inclined surface upon its upper side, the inclination of said surface being upward from the pivoted side to the opposite side of said door.

15

Signed by me, this 18th day of May, 1908
PIERRE PLANTINGA.
